UNITED STATES PATENT OFFICE.

FRANKLIN T. DAVIS, OF MOUNT VERNON, ASSIGNOR TO HIMSELF, AND
AUGUSTUS P. ROCKWELL, OF EAST CHESTER, NEW YORK.

COMBINED LATCH AND LOCK.

SPECIFICATION forming part of Letters Patent No. 349,571, dated September 21, 1886.

Application filed June 10, 1886. Serial No. 204,769. (Model.)

To all whom it may concern:

Be it known that I, FRANKLIN T. DAVIS, a citizen of the United States, residing at Mount Vernon, in the county of Westchester and State of New York, have invented new and useful Improvements in Combined Latches and Locks, of which the following is a specification.

This invention relates to a lock for doors; and it consists of certain novel features of construction, which are fully pointed out in the following specification and claims, and illustrated in the accompanying drawings, in which—

Figure 1 represents a view of my lock when the face-plate has been removed, showing the position of the parts as it is being unlocked from the outside by the key. Fig. 2 is a similar view showing it unlocked and in position to have the latch thrown back by means of the door-knobs. Fig. 3 is a similar view showing it locked from the inside. Fig. 4 is a vertical section in the plane xx , Fig. 2. Fig. 5 is a section in the plane yy , Fig. 4. Fig. 6 shows a modification of my lock. Fig. 7 is a section in the plane zz , Fig. 6.

Similar letters indicate corresponding parts.

In the drawings, the letter A designates the casing of a "mortise" lock, which is closed by the face-plate B, and provided with flanges C, by means of which it is secured to the door.

D is the latch, turning on a pivot, a , rising from the casing. This latch, which, when the door is closed, catches behind a keeper, (not shown,) which is usually secured to the door-casing, may be turned on its pivot and disengaged from said keeper by either of the lever-spindles E E', which carry the knobs F F', the operation of which will be hereinafter more fully described. From the rear end of the latch

D extends a tail, b, which, when the lock is locked by the key, (see Fig. 1,) rests against a finger, c, projecting from the lower end of the tumbler G. This tumbler turns on a pivot, d, and its upper end is provided with an arm, e, against which the key H operates, and which is engaged by a swinging catch, I, which turns loosely on a pivot, f, rising from the casing A. This swinging catch is also actuated by the key, and when the shoulder g on its lower edge

rests under the arm s on the tumbler, the lat-

ter is held in such a position that the finger c on its lower end comes under the tail b of the latch D, and locks the same in the position shown in Fig. 1. When it is desired to release the latch, the key H is inserted in the lock and turned in the direction indicated by the arrow in Fig. 1, which will cause it to turn the swinging catch I on its pivot toward the left until the shoulder on the same shall have been swung from under the arm e of the tumbler. As the rotation of the key is continued, it will also act on the arm e, moving it downward, and thereby turning the tumbler on its pivot, and permitting the swinging catch I to swing back to the position shown in Fig. 2, over the arm e, thereby holding the tumbler in that position, leaving the latch D free to turn on its pivot a to the position shown in dotted lines in Fig. 2, when actuated by means of the knobs, thus enabling the door to be opened. When it is desired to again lock the latch D, the knobs being in their normal position, as indicated in full lines in Fig. 4, the key is rotated in a direction opposite to that indicated by the arrow in Fig. 2, thereby swinging the shoulder g of the swinging catch I off from the tumbler, which action permits the latter to turn on its pivot by its own gravity until the position shown in Fig. 1 is attained, when the shoulder g on the swinging catch will again swing under the arm e of the tumbler, as shown in dotted lines in Fig. 1, and the finger c will pass under the tail b and lock the latch in its outer position. It will be observed that the catch I, when released from the operation of the key, swings toward the right by means of gravity, in which it is aided by the operation of the coiled spring z, wound around the pivot f, one end, y, of the spring bearing against the top of the casing A, and the other end being hooked to the catch I. I provide the catch I with a stop, X, which projects from its hub and extends toward the casing A, so as to bear against the casing at the end of the vibration of the catch toward the tumbler G, and stop the swing of the catch in that direction, and prevent the catch from covering the key-hole.

It will be understood that the lock may be locked by the key from either side of the door;

but I prefer to apply the key from the outside only. After the lock has been unlocked from the outside by the key, as above described, and the latch is free to turn on its pivot, I depress 5 the tail end of the latch by the spindle E, which is pivoted by a horizontal pivot, q, in an escutcheon, J, secured to the outside of the door, and which carries the pendent knob F. When 10 this knob is raised, the inner end of the spindle, which rests on the tail b of the latch, is depressed, pushing the tail of the latch down with it, and turning the latch sufficiently on its pivot a to bring it completely into the casing, as shown in dotted lines in Fig. 2, and 15 out of the "keeper" on the door-casing, thereby permitting the opening of the door.

To lock the door from the inside, I provide a rotating hub, K, which has its bearing in the face-plate and carries a hook, h. This hub is 20 provided with a slot, i, extending through it, through which opening passes the hinged spindle E'. The spindle, in addition to its oscillating motion, can also be rotated, and by turning the same the hub K is also turned until the 25 hook h passes beneath the tail b of the latch, thereby firmly locking the same in position. (See Fig. 3.) When it is desired to open the door from the inside, the spindle E' is turned in the opposite direction, which action will, 30 by turning the hub K back again, cause the hook h to release the tail b of the latch, bringing the parts K and h back to the position shown in Fig. 2. The pendent knob F' is then raised to the position shown in dotted lines in 35 Fig. 4, thereby depressing the tail b of the latch, bringing the same completely into the lock-casing and permitting the door to be opened.

Each of the spindles E and E' is made in two sections, which are connected by a hinge, 40 F², each section being provided with a shoulder, r, which shoulders, when brought against each other, serve to limit the motion of the hinge-joint. The spindle E' is made in this form to indicate the position of the rotating 45 hub K, while the spindle E may be of one piece, but in the example shown in the drawings is made to correspond to the other spindle, E'. When the door is unlocked, the parts of the lock being in the position shown in Fig. 50 2, the knob F' will hang, as shown in full lines in Fig. 4; but when the door is locked from the inside the knob will stand out at right angles to the door, thereby indicating that the door is locked, and that this knob must be 55 turned to the pendent position before it can be opened.

To permit the formation of a close joint between the spindle E' and the escutcheon L, I pivot said spindle in a thimble, M, which rotates easily in the escutcheon; but this thimble may be dispensed with and the spindle be arranged to rotate loosely in the escutcheon, being held from dropping out by a shoulder formed on the spindle. From this description 60 and the drawings it will be understood that my lock can be locked and unlocked inde-

pendently either from the inside or the outside, the locking of the latch D being accomplished from the outside by the key by means of the tumbler G and its tail-piece c, and from the inside by the knob F', spindle E', and hub K, and hook h by the engagement of the hook h with the tail-piece of the latch. 70

It is obvious that I can apply either of my locking devices so that they can be operated 75 from both sides; but one of the objects of my invention is to provide a lock which cannot be opened from the outside when locked from the inside, and vice versa, and for this reason I have provided the independent latch-locking 80 device, as shown and described.

Fig. 6 shows a modification of my lock, in which the tumbler rests in a notch in the latch, D, instead of catching under the tail shown in the other figures, and the lock can be locked 85 or unlocked by the key from either side of the door. This figure also shows a reversible latch, the convex part thereof N, which comes in contact with the keeper on the door casing or frame, being detachable and provided with 90 steady-pins m, which fit holes n in the body of the latch, to which the detachable portion is secured by a screw, o. By properly placing this detachable portion of the latch the lock may be applied to doors which swing either 95 to the right or to the left. A guard-partition, p, of about the same depth as the casing A, is placed in the casing of the lock so as to cover the openings for the spindles, and to prevent tampering with the lock through these openings. 100

In all the figures I have shown the tumbler G and the swinging catch I made of one solid piece of metal; but it is obvious that either or both may be made of two or more separate 105 plates, and, together with proper key-guards, would greatly add to the security of the lock and increase the difficulty of picking.

When the latch D is free both from the locking-hook h and the catch c of the tumbler, it is 110 free to be operated by the knobs F F', through their respective spindles E E', so that the latch can be withdrawn from its keeper from the outside as well as from the inside by lifting the appropriate knobs, and thereby causing 115 their respective spindles to bear down upon the tail-piece of the latch, when the latch is to be withdrawn from the keeper and the door opened. I do not, however, desire to confine myself to this form of independent spindle 120 for actuating the latch, since said spindles, instead of being mounted on pivots, so that they act as levers, may be constructed to rotate, and provided with eccentrics or cams, which, as the said spindles are rotated, will act on 125 the tail b, turn the latch on its pivot, and draw the same into the lock-casing.

What I claim as new, and desire to secure by Letters Patent, is—

1. The combination, with the latch D, the 130 tumbler G, the swinging catch I, and a key formed to actuate both the tumbler and the

catch, of the spindles E E', each constructed to actuate the latch independent of the other substantially as described.

2. The combination, with the latch D, the 5 spindle E, the tumbler G, the swinging catch I, and a key formed to actuate both the tumbler and the catch, of the hub K, the rotating hook h, constructed to engage the latch, and the spindle E', constructed to operate said 10 hook, substantially as described.

3. The combination, with the latch D, of the hub K, the rotating hook h, constructed to engage said latch, the sectional spindle E', constructed to rotate said hook, the hinged 15 connections between the sections of said spindle, and the shoulders r, substantially as described.

4. The combination, with the pivoted latch D, provided with a tail, b, of a pivoted tumbler, G, carrying on one side of its pivot a finger, c, constructed to engage said tail, and on the opposite side of its pivot an arm, e, a swinging catch, I, adapted to engage said arm, a key formed to actuate both the tumbler and the catch, means, substantially as described, for 20 actuating the latch from one side of the lock, the hub K, the rotating hook h, and the spindle E', constructed to operate said rotating hook and constructed to actuate the latch from the other side of the lock, substantially as 25 shown and described.

5. The combination, with the pivoted latch D, provided with a tail, b, of a pivoted tumbler, G, carrying on one side of its pivot a finger, c, constructed to engage said tail, and on the opposite side of its pivot an arm, e, a swinging catch, I, adapted to engage said arm, a key formed to actuate both the tumbler and the catch, means, substantially as described, for 30 actuating the latch from one side of the lock, the hub K, the rotating hook h, and the spindle E', constructed to operate said rotating hook and constructed to actuate the latch from the other side of the lock, substantially as 35 shown and described.

6. The combination, with the latch D, of the hub K, carrying the hook h, the pivoted lever-spindle E', constructed to rotate said hook and to actuate the latch, and the thimble M, 40 carrying said spindle, substantially as described.

In testimony whereof I have hereunto set my hand and seal in the presence of two subscribing witnesses.
